Inventor
Adoniram J. Cook.

UNITED STATES PATENT OFFICE.

ADONIRAM J. COOK, OF WESTERLO, NEW YORK.

METAL AEROPLANE.

1,363,569.

Specification of Letters Patent. Patented Dec. 28, 1920.

Application filed July 8, 1920. Serial No. 394,709.

To all whom it may concern:

Be it known that I, ADONIRAM J. COOK, a citizen of the United States, residing in Westerlo, in the county of Albany and State 5 of New York, have invented certain new and useful Improvements in Metal Aeroplanes, of which the following is a specification.

The object of this invention is to provide 10 an improved construction in metal aeroplanes, in which the wings are separate and detachable so that the apparatus may be stored in comparatively small space.

A further object is in the manner of 15 structuring and assembling the brace elements whereby a maximum of strength and stability of construction is attained with a minimum of weight.

These and other objects, which will be 20 come apparent as the description progresses, are attained by the novel construction, combination and arrangement of parts, herein-after described and shown in the accompanying drawings, forming a material part 25 of this disclosure, and in which:—

Figure 1 is a perspective view of a metal 20 aeroplane, partly dismembered, made in accordance with the invention.

Fig. 2 is an enlarged transverse sectional 30 view taken through one of the wings.

Fig. 3 is a further enlarged fragmentary 35 sectional view of the same.

Fig. 4 is a perspective view showing the 40 construction and assembly of the wing elements.

Fig. 5 is an enlarged fragmentary perspective view showing the wing frame structure.

Fig. 6 is a similar view of one of the metal 45 struts employed.

Fig. 7 is a perspective view showing further details of construction.

Referring to the drawings in detail the 50 numeral 15 designates in general the fuselage or body of the aeroplane, the same being of conventional type of construction, provided with a propeller 16 at the front, horizontal and vertical rudders, respectively 55 17 and 18 at the rear and a cock pit 19, in 60 which the several control devices are accessible to the aviator.

In the biplane as shown in Fig. 1, the

lower wing section 20 has upon its upper side a platform 21 to which is attached the fuselage 15, the platform extending to engage the mating section 22, by means of 55 bolts or like fastenings passing through the respective openings 23 and 24.

The corresponding upper wing section 26 has a plate 27 directly over the fuselage, to 60 which may be connected the section 28 by similar fastening means passing through the openings 29 and 30.

Between the upper and lower sections 20 and 26, and 22 and 28 are a plurality of 65 posts 32 braced by diagonally disposed guy rods 33, it being understood that each section is separate and independent in itself.

It will be noted the elements 21 and 27 are so arranged as to produce a bracing effect 70 making the aeroplane strong and reliable at the middle of the fuselage where strength is most required.

Extending between the platform 21 and plate 27 are channel posts 35 (see Fig. 6) 75 having flanged ends 36 containing openings 37 for rivets by which they are firmly held in assembled position; other openings 38 provide convenient means for bolting or riveting these posts direct to the fuselage 80 15, (see Fig. 1).

The wing structure shown in detail in Figs. 2, 3, 4, 5 and 7, constitute an important feature of the invention.

Each is comprised of a plurality of rafters 85 or ribs formed of pairs of rolled angles, generally indicated by the characters 40 and 40', spaced and positioned as best shown in Fig. 5.

These ribs are bent to the shape shown in 90 Fig. 2, the vertical elements being notched, as at 41, to permit bending, forming a bowed front end 42 from which the slightly convex bottom 43 extends rearwardly, the upper elements 44 presenting a convex surface, 95 gradually approaching the lower element toward the rear end, while secured between them is the filler rail 45.

These several ribs are reinforced and maintained in shape by angularly disposed 100 struts 46 secured between the spaced vertical elements of the rib angles in parallel planes, while at suitable points, near the front and rear, the ribs are connected in

spaced relation by plates 48 bent to form tenons 49 disposed between the angles and extending the full length of each wing element.

- 5 To the adjacent sides of the plates are attached paired angles 50 having between them transversely disposed diagonal struts 51, the entire structure being securely riveted as indicated and forming a firm rigid 10 frame connected by the posts 32, into bi-plane wings of stability and lightness.

The metal cover plates 52 are held to the frames in the manner shown in Fig. 5, the edges of the plates being pressed into the 15 space between the angles 40 and 41, by tenons 53 formed with plates 54, secured to the horizontal elements of the angles by screws 55. A U shaped metal strip 56, suited to the rib ends 42, supports the plates, this 20 forming impervious joints, which, if desired, may be readily broken for the removal or replacement of the plate portion of the wings.

From the foregoing it will be seen that 25 the wing elements may be readily detached from the floor or platform 21 and roof plate 27, permitting the entire structure to be stored in a limited space, and that the structure of the wings is such as to attain the objects sought.

Having thus described my invention, what I claim as new and desire to secure by Letters Patent, is:—

1. An aeroplane wing comprising pairs of 35 rolled angles bent reentrantly, their limbs being arranged respectively adjacent and laterally, plates overlying the lateral limbs, tenons formed with said plates, said tenons extending inward between the adjacent 40 limbs, lattice elements extending between the opposed limbs from one section to the other and cover plates engaging between the tenoned plates and walls of adjacent angles whereby they are held in tension.

45 2. An aeroplane wing comprising pairs of rolled angles bent reentrantly to present substantially parallel upper and lower

frame elements, lattice bars connecting between said elements, thin metal cover plates arranged in overlapping relation over said 50 angles and tenoned cover plates secured to said angles, their tenons forcing the overlapping edges of said cover plates between the inner sides of said pairs of angles against the ends of said lattice bars. 55

3. An aeroplane wing comprising pairs of rolled angles bent reentrantly to present substantially parallel upper and lower frame elements, lattice bars connecting between said elements, transverse angles connecting between adjacent pairs of the rib angles, metal strips interposed at the joints therebetween, said strips being bent at their centers tightly upon themselves and entered between said pairs of angles, plate coverings 60 extending over said rib angles and means for rigidly engaging the overlapping edges of said plate covering between the angles. 65

4. An aeroplane wing comprising a plurality of ribs formed of pairs of rolled angles 70 and bent upon themselves, lattice connections between the upper and lower rib elements held between the angles, lattice beams connecting said ribs in spaced relation, a rail at the rear of the ribs, a rolled element at 75 the front, metal cover plates disposed over said ribs, rail and rolled elements, and means engaging between the angles for holding the plates in position.

5. An aeroplane wing comprising a plurality of ribs formed of pairs of rolled angles and bent upon themselves, transverse beams composed of angles and lattice elements engaging said ribs whereby they are held in rigid spaced relation, connections at 80 the ends of said ribs, plate strips having tenons adapted to enter between each pair of rib angles clamping coverings therebetween, and means for engaging said strips to said angles whereby the covering is held 85 taut along its lateral edges. 90

In testimony whereof I have signed my name to this application.

ADONIRAM J. COOK.
